UNITED STATES PATENT OFFICE.

CONRAD SCHÜTZ, OF PHILADELPHIA, PENNSYLVANIA.

LATCHING MECHANISM.

1,315,991.

Specification of Letters Patent. Patented Sept. 16, 1919.

Application filed April 16, 1918. Serial No. 228,854.

To all whom it may concern:

Be it known that I, CONRAD SCHÜTZ, a citizen of the United States, residing in the city of Philadelphia, county of Philadelphia, and State of Pennsylvania, have invented certain Improvements in Latching Mechanisms, of which the following is a specification.

This invention is a latching mechanism adapted for general use but designed particularly for use with refrigerator doors, and its primary purpose is to provide a fastener of simple and efficient character which is applicable to either a right or a left hand door.

The characteristic features of my improvements will appear from the following description and the accompanying drawings in illustration thereof.

20 In the drawings, Figure 1 is front elevation of an embodiment of my invention applied to door and jamb sections; Fig. 2 is a sectional view on the line 2—2 of Fig. 1; Fig. 3 is a sectional view on the line 3—3 of Fig. 2; Fig. 4 is a side elevation of the detached keeper; Fig. 5 is a sectional view on the line 5—5 of Fig. 2; Fig. 6 is a front elevation of a modified form of my invention; Fig. 7 is a sectional view on the line 7—7 of Fig. 6; Fig. 8 is a sectional view on the line 8—8 of Fig. 7; and Fig. 9 is a sectional view on the line 9—9 of Fig. 7.

As illustrated in Figs. 1 to 5 inclusive, a door section A has fixed thereto a base 1 from which project bearings 2, 2', having journaled therein the shaft 3. A collar 4, fixed to the shaft by a set screw 4', is provided with a lug 5 containing recesses 5' in which are engaged the ends 6' of springs 6, the latter being coiled on studs 7 fixed to the base and having ends 6'' bearing against the farther studs 8 fixed to the base. Studs or a split stud 9 is fixed to the base between the ends 6' and limits their inward movements. The springs 6 tend to hold the lug 5 in its median position.

The shaft 3 has fixed on the end thereof beyond the standard 2, an arm 10 provided with a bearing 11 on which is journaled a roller 12. A handle 13 is held by a set screw 13' on the shaft 3, either in the position shown in Fig. 1 or in the reverse position when the device is reversed for use on a reversely hung door, the handle being removable by loosening the set screws 4' and

13' so as to permit the shaft to be moved longitudinally through the bearing 2'.

Stops 14 on the base 1 are adapted for engaging the handle to positively limit its movement and the movement of the arm 10. 60

A lever 31^a, fulcrumed on the bearing 32^a forming a part of the base, is adapted to be rocked by the push rod 31^b which is pivotally connected thereto and extends through the base and the door, the opposite 65 end of the lever acting between the parts of the split stud 9. A link 31^c connects the lever with either of the lugs 4'' on the collar 4 so that by operating the push rod 31^b and rocking the lever 31^a the shaft 3 and the 70 arm 10 are rocked, either to the right or left, depending on the connection of the link.

A keeper 15, fixed to the jamb B, is provided with an arrow-head or V-shaped cam 75 16 having oppositely inclined bearing surfaces 17 and shoulders 18 partially closing recesses 19 in the keeper. A cover plate 15' may be used to complete the closure of a 80 recess 19 when not in use.

In operation, with the mechanism in the position shown in Fig. 1, the closure of the door brings the roller 12 into contact with the lower inclined surface 17 of the keeper 15, the arm 10 being deflected thereby 85 against the action of the lower spring 6, until the roller passes the cam 16 and enters the lower recess 19, when the recoil of the spring moves the roller to position under the shoulder 17, thereby latching the door. 90 To open the door, the handle 13 is pulled or the rod 31^b is pushed outwardly to rotate the shaft 3 and move the roller 12 beyond the shoulder 17, thereby permitting the withdrawal of the roller from the recess and 95 the opening of the door.

It will be understood that to apply the mechanism to a right hand door, it is only necessary to invert such mechanism and reverse the handle 13 by loosening its set screw 100 and the set screw 4' sufficiently to permit the withdrawal of the shaft 3 from its bearing, the connection of the link 31^c being reversed and the plate 15' being reversed if used.

As shown in Figs. 6 to 9 inclusive, the base 105 20 has thereon two pairs of bearings 21, 21' in which are journaled the parallel shafts 22, 22'. Collars 23, 23' are fixed on the respective shafts by set screws 33'' and have depending lugs 24, 24' containing recesses 24'' 110

in which are engaged free ends of springs 25 fixed to lugs 26 at the rear of the base and held in adjustable relation to the parts 24 and 24' by means of set screws 27 carried by 5 the lugs 28 on the base.

The collar 23 contains a recess 23^a and the collar 23' is provided with a tooth 23^b extending into the recess, whereby the collars are geared together and the shafts moved in 10 unison.

The shafts 22 and 22' have fixed on the ends thereof the respective arms 28, 28' on whose bearings 28^a and 28^b are journaled rollers 29, 29'. The shafts are operable in 15 unison by a handle 30 fixed by a set screw 30' on the shaft 22' when the mechanism is used as in the drawing, or to the shaft 22 when the mechanism is to be used in the reverse position on a reversely hung door.

20 A lever 31, fulcrumed on a bearing 32, has at one end a recess 31' in which the tooth 23^b is engaged, and at the other end is pivotally connected with a push rod 33 which extends through the base 20 and the door A to 25 permit the operation of the latching mechanism to open the door from the inside.

This form of latching mechanism is used with the keeper 15, described, but the cover plate 15' is omitted from the keeper, and 30 when the door is closed the rollers 26, 26' simultaneously engage both inclined surfaces 17 of the cam 16 and the arms 28 are moved in opposite directions, against the actions of the springs 25, until they enter the openings 35 19, when they are moved together by the action of the springs and engage the rollers 29 under the shoulders 17. To unlatch the door, the handle 30 or the push rod 33 is operated to rock the shafts 22 and 22' and 40 spread the arms 28 and 28' so that the rollers 29 and 29' clear the shoulders 17.

It will be understood that to adapt this form of construction to an oppositely hinged door, it is only necessary to reverse the

handle and apply it to the shaft 21', which 45 is readily done by loosening the set screws therein and in the collars 23, 23'.

Having described my invention, I claim:

1. In a device of the character described, the combination with a keeper and a base 50 having bearings thereon, of a shaft journaled in said bearings, said shaft having an arm thereon adapted for engaging said keeper and a spring mounted on said base and connected with said shaft for effecting 55 the engagement of said arm with said keeper.

2. In a device of the character described, the combination with a keeper and a base 60 having bearings thereon, of a spring mounted on said base, and a shaft journaled in said bearings, said shaft having an arm for engaging said keeper and a lug for engaging said spring.

3. In a device of the character described, 65 the combination with a keeper having oppositely inclined surfaces and means opposite each surface for engaging a latch, of a base having bearings thereon, rocking means journaled in said bearings, said rocking 70 means having latching means fixed thereto, and resilient means mounted on said base and adapted for acting in opposite directions to return said rocking and latching means from their deflected to normal position 75 in locking engagement with said keeper.

4. In a device of the character described, the combination with a keeper, of a base 80 provided with bearings, springs mounted on said base, a shaft journaled in said bearings, said shaft having thereon a latching device adapted for engaging said keeper and a lug acting between the ends of said springs, and a handle on said shaft for operating it.

In testimony whereof, I have hereunto set 85 my name this 15th day of April, 1918.

CONRAD SCHÜTZ.
